[57] CLAIM

The ornamental design for a game paddle, substantially as shown and described.

DESCRIPTION

FIG. 1 is a plan view of a game paddle showing the new design;

FIG. 2 is an end elevation view of the game paddle of FIG. 1; and

FIG. 3 is a side elevation view of the game paddle of FIG. 1.

The tethered ball has been omitted from FIGS. 2 and 3 for convenience of illustration;

The opposite side of FIG. 1 is plain and unornamented.
